UNITED STATES PATENT OFFICE.

JAMES R. RICKETTS, OF LOS ANGELES, CALIFORNIA.

IRON.

1,073,440.

Specification of Letters Patent. Patented Sept. 16, 1913.

Application filed May 4, 1912. Serial No. 695,184.

To all whom it may concern:

Be it known that I, JAMES R. RICKETTS, a citizen of the United States, residing at Los Angeles, in the county of Los Angeles 5 and State of California, have invented new and useful Improvements in Irons, of which the following is a specification.

This invention relates to irons, such as sad irons, pressing irons, tailors' gooses and 10 the like, and it has for its object to provide improvements in devices and implements of the nature stated, which will be superior in point of simplicity and inexpensive of construction in combination with economy in 15 utilization of heat, convenience in use, positiveness and effectiveness in operation, and durability, and which will be generally superior in efficiency and serviceability.

In the main, the invention has for its object to provide an iron having a plurality 20 of working surfaces or working surface portions, means for heating the surfaces, and means for changing or alternating the surfaces or surface portions. Preferably, 25 the heating means are internally arranged, and the means for varying or alternating the surfaces presented to the work include a handle and locking means associated therewith, and operating upon the body of 30 the iron. The heating means, in a preferred form, include a burner which serves as a working center for reversing the body of the iron or shifting it so as to present different working surfaces.

35 In practising the invention, great economy in utilization of heat is produced, as the heat absorbed by the body of the iron is taken from more than one surface thereof, instead of becoming dissipated and lost. Furthermore, a fresh hot surface is always 40 available, after use of another surface has reduced the temperature thereof, and such surface is available without waiting for re-heating in contact with a stove or other independent heating means.

45 With the above and other objects in view, the invention consists in the novel and useful provision, formation, combination, association and relative arrangement of parts, 50 members and features, all as hereinafter described, shown in the drawing and finally pointed out in claims.

In the drawing: Figure 1 is a side elevation of an iron constructed and organized in accordance with the invention; 55 Fig. 2 is a longitudinal sectional view of the same taken upon the line X^2-X^2 , Figs.

3 and 4; Fig. 3 is a rear end view of the iron; Fig. 4 is a transverse sectional view of the iron, taken vertically upon line 60 X^4-X^4 , Fig. 2; and Fig. 5 is a detailed fragmentary sectional view, taken upon the line X^5-X^5 , Fig. 3.

Corresponding parts in all the figures are denoted by the same reference characters.

Referring with particularity to the drawing, A designates the body and B designates the handle of a pressing iron or sad iron organized in accordance with the invention, the body comprising two spaced parallel working surfaces, or working surface portions or members, 5 and 6, which consist of thick metallic plates and are connected at their front ends by a thin vertical 70 plate 7, and at their rear ends by a thin vertical plate 8, and at their sides by thin vertical plates 9 and 10. Certain of said plates, such as 9 and 10, are provided with ports or openings 11, for admission of air 75 within and circulation of air through the box-like iron body A.

The heating means C, comprises a burner tube 12, extending through the end plates 7 and 8, rotatively therein, in the longitudinal center axis of the body A, such tube having a holding cap 12, at the forward end, and the inner end or hub 13, of the handle member B, being fixed to the rear end of the tube 12. The body A may 90 thus be rotatively swung upon the burner tube 12, relative to the handle member B. The hub 13 is held to the tube 12, by a pin 14, or the like; and said hub is enlarged 95 to form an air intake chamber 15, communicating with the tube 12, as likewise communicates a gas feed nipple 16, which receives its supply from a suitable tube or pipe, not shown. The shank 17, of the handle member B, rises from the hub 15, 100 and carries the grip 18, which projects above the body A, being spaced therefrom.

D designates shifting or reversing means for the body A, the same comprising a lever arm 19, pivoted to the handle shank 17, 105 as at 20, rearwardly of such shank, intermediate of the ends of said lever, said lever arm having at its upper end a head 21, to be pressed by the hand which grasps the grip 18; compression means, 22, consisting of a coil spring between the upper end of the lever arm and the shank, being provided, normally to hold the head 21 away from the upper end of the shank.

d designates locking means associated with the reversing means D, and comprising a finger 23, fixed to the lower end of the lever arm 19, and playing through a hole 24, 5 in the lower portion of the shank 17, so as to enter and be withdrawn from holes 25 and 26, in the end plate 8, respectively, adjacent to the body plate 5, and the body plate 6, and in a common plane passing 10 through the axis of the burner tube 12. Adjacent to the side portions, respectively, of the end plate 8, are recesses 27 and 28, respectively, lying in a common plane passing through the axis of the tube 12, at right 15 angles to the plane passing through the holes 25 and 26. These recesses taper in depth in opposite directions from one extremity to the other, so as to produce inclined inner walls 27^a and 28^a, respectively. 20 Within the body A, are formed a plurality of transverse webs 29, of varying proportions throughout the extent of each, as shown in Fig. 4, springing from the plates 5 and 6, and acting to absorb heat radiated 25 from the burner tube 12, which has the usual jet openings 12^a, so as to convey such heat to the box-like body A, and particularly the working plates 5 and 6 thereof.

The operation, method of use and advantages of the improvement in irons constituting the invention will be readily understood from the foregoing description, taken 30 in connection with the accompanying drawing and the following statement: The heat 35 produced at the burner tube 12, constituting the heating means C, is absorbed by the iron body A, and particularly the working plates 5 and 6, thereof, which plates constitute the working surface portions alternately used in the ironing operation. As 40 one plate is being used the other is storing up heat for use when the body A has been reversed by the shifting or reversing means D, the manner of use of which is apparent. To shift or reverse the body, the 45 head 21, of the lever arm 19, is pressed inwardly until the finger 23 is withdrawn from, respectively, the hole 25 or 26, in the iron body, releasing the handle member B, 50 which is swung to one side by rotating the burner tube 12, in the iron body, until the finger 23 enters one of the recesses 27 and 28. The grip 18 is then raised or given a sharp upward swing, which completely 55 reverses the body and permits the finger 23 to enter the other hole, 25 or 26, locking the handle member and body against relative rotation. In this operation the finger 23 rides out of the recess over the inclined bottom wall 27^a or 28^a, thereof; or, the body 60 may be half reversed with the finger in the recess, and the finger may then be disengaged from the recess and caused to enter

the second hole and the reversing operation then completed. The spring 22 normally keeps the finger in one of the holes. 65

In using the invention, as soon as one heated ironing surface becomes chilled or partly cooled there is a fresh hot surface ready, and the depleted surface is again 70 heated while the hot surface is being employed. The shifting or reversing means D enable the body to be reversed without lifting it from the board or table, if desired, the locking means *d*, with the aid of 75 the recesses 27 and 28, assisting in the easy task of rolling the body over into new position. The heating means being inherent, no time is wasted in re-heating the surfaces by any outside sources of heat. 80

It is manifest that many changes may be made in the form, construction, organization and combination of parts, members and features, at variance with those disclosed, without departing from the spirit of the invention. 85

Having thus described my invention, I claim and desire to secure by Letters Patent:

1. A sad iron or the like, comprising a 90 body having a plurality of working surfaces, means upon which the body is mounted to swing, a handle member mounted upon said last named means to swing relative to the body, the body being provided with locking openings and with an intermediate recess for the reception of means to swing the body, and means upon the handle member arranged to enter said openings and said recess respectively to lock the body relative to the handle member and to swing the body responsive to force applied in swinging the handle member. 95

2. A sad iron or the like, comprising a 105 body having a plurality of working surfaces, means upon which the body is rotatably mounted, a handle member mounted to swing upon said last named means, the body being provided with locking openings and with alternately arranged oppositely 110 tapering recesses formed to receive means for rotating the body and spaced ninety degrees apart with respect to rotation, and means upon the handle member respectively adapted to co-act with said locking openings 115 and with said recesses to lock the body member in position resultant upon rotation and to rotate the body member responsive to force applied through the handle member.

In testimony whereof, I have signed my 120 name to this specification in the presence of two subscribing witnesses.

JAMES R. RICKETTS.
